UNITED STATES PATENT OFFICE

2,481,277

NUMBER WHEEL GAME WITH RECORDING ATTACHMENT

William J. Balaun, Akron, Ohio

Application February 4, 1947, Serial No. 726,414

4 Claims. (Cl. 346—14)

1

The invention relates to mechanically operated games and more particularly to that type of game in which the element of chance is emphasized.

Briefly the invention contemplates the provision of a game apparatus in the form of a spinning game in which a plurality of rotatable number wheels are set in motion by mechanical means and which will register a number when they come to a stop, the machine also being provided with a paper tape upon which the operator may write a number before operating the machine, matching his wits against the machine by making a guess of the number which will be registered upon the machine when the number wheels come to a stop, means also being provided for automatically printing upon the tape the number which is registered upon the number wheels with each operation of the machine so that a written record remains upon the tape of the number which the operator has guessed before operating the machine and the number which is registered by the number wheels upon each operation of the machine.

It is an object of the invention to provide a machine of this character in which rotary number wheels are mechanically set into motion and after a variable period of time of rotation are brought to rest so as to visually indicate or register a number having digits corresponding to the number of said wheels.

Another object is to provide such a machine with means for automatically printing upon a paper tape the number which is visually indicated by the number wheels.

A further object is to provide a machine of this character in which each of the number wheels is hollow and provided around its interior with a series of depressions corresponding in number and position to the numbers upon its peripheral surface, a metal ball being located within the interior of each hollow number wheel and tending to come to rest at the lowest possible point within the wheel so as to always stop the wheel with one of the depressions at the bottom of the wheel so as to assure each wheel coming to rest in position to display one of the numerals thereon through a sight glass or window in the housing of the machine and not at a point between such numerals.

A still further object is to provide a rotatable printing wheel operatively connected to the rotatable number wheels so as to print the numerals registered or visually displayed by each wheel upon coming to rest after each rotation thereof.

Another object of the invention is to provide such a machine in which means is provided for

2

the operator to first write a number upon the paper tape on which the printing wheels later print the number at which the number wheels come to rest.

5. Still another object is to provide a machine of this character in which after the number has been written upon the paper tape the tape is automatically moved by the operation of the machine so as to move the portion thereof having 10 the written number thereon to a point where it is visible beneath a transparent sight glass or window but inaccessible from the exterior of the machine.

A further object of the invention is to provide 15 a machine of the character referred to in which all of the above mentioned operations are automatically carried out in sequence after the actuating handle is operated.

The above objects together with others which 20 will be apparent from the drawings and following description, or which may be later referred to, may be attained by constructing the improved spinning game in the manner hereinafter described in detail and illustrated in the accompanying drawings in which:

25 Figure 1 is a perspective view of a machine constructed in accordance with the invention with the outer housing removed to show the operating mechanism;

Fig. 2 a vertical, sectional view through the machine;

Fig. 3 a top plan view of the machine with the housing thereon; and,

Fig. 4 a front elevation of the complete machine with the housing thereon.

35 The apparatus includes a frame comprising the base plate 10 and side plates 11 upon which all of the movable parts of the mechanism are mounted, as best shown in Fig. 1 of the drawings, 40 in which the base plate and side plates are shown in dot and dash lines for the purpose of more clearly illustrating all of the working parts of the machine.

45 Located within the upper, rear portion of the frame is a shaft 12, upon which are independently journalled a plurality of spaced number wheels 13, upon each of which is fixed a sprocket wheel 14. A shaft 15 is mounted between the side plates 11, parallel to and forwardly of the number 50 wheel shaft 12, and the printing wheels 16 are independently journalled thereon.

55 These printing wheels correspond in number to the number wheels 13 and each printing wheel has a sprocket wheel 17 fixed thereto and connected, as by the sprocket chain 18, to the sprock-

et wheel 14 of the corresponding number wheel so that when the number wheels are independently rotated upon their shaft each printing wheel will be rotated in unison with the corresponding number wheel.

Each number wheel has around its periphery a series of numerals from 1 to 9 and 0, and each printing wheel has a corresponding series of raised or embossed numerals around its periphery in the form of printing type so as to print upon the paper tape 19 as will be later described in detail.

This paper tape is withdrawn from a stock roll 20, such as is common in adding machines, cash registers and similar apparatus, this stock roll being mounted upon the shaft 21 which may be journaled between the side plates 11 at the forward lower portion of the machine.

The paper tape 19 is withdrawn from the stock roll and passed up over the paper guide plate 22, mounted between the side plates 11 at the upper forward portion of the machine, and then passes downwardly in front of, and adjacent to, the printing wheels 16, over the paper guide roller 23 and is wound upon the used paper spool 24 which is journaled upon the shaft 25, the ends of which are slidably mounted in the horizontal slots 26 in the side plates 11.

Coil springs 27 are connected to the end portions of the shaft 25 as indicated at 28 and extend rearwardly and downwardly to the lower rear corner of the machine, the other ends of these coil springs being connected to the side plates 11 as indicated at 29, so as to normally urge the used paper spool rearwardly in the horizontal slots 26 and into contact with the rubber roll 30 which is journaled upon the main actuating shaft 31, which shaft is journaled in the side plates 11.

The operating lever 32 has an angular inturned elbow 33 at its lower end for rigid connection to the outer end of the main actuating shaft and may be provided with a knob or handle 34 at its upper end to be grasped by the operator to set the machine in operation as will be later fully described in detail.

The main actuating arm 35 is rigidly connected to the main actuating shaft 31 and a pawl 36 is pivoted upon the lower portion thereof as indicated at 37, the lower end of said pawl being normally engaged by gravity with the ratchet wheel 38 which is fixed to the adjacent end of the rubber roll 30, while the upper end 39 of the pawl normally extends above the rearwardly curved central portion 40 of the main actuating arm.

A pawl stop in the form of a stud or the like, as indicated at 41, is fixed upon the inner side of the adjacent side plate 11 in the path of the upper end 39 of the pawl so as to release the lower end of the pawl from engagement with the ratchet 38 at a pre-determined point in the movement of the main actuating arm.

A coil spring 42 is connected at one end to the main actuating arm as indicated at 43 and at its other end to the adjacent side plate 11 as indicated at 44 so as to normally urge the main actuating arm and operating lever backward to the normal position as indicated in Fig. 1.

At the upper end of the main actuating arm is a rigid finger 45 for operating the ribbon and stamping actuating bar 46 as will be later described. The free upper end of the main actuating arm is forwardly curved as at 47 and has the pawl 48 pivoted thereon as indicated at 49.

The inturned stop lug 50 upon the main actuat-

ing arm contacts the forwardly disposed tail 51 of the pawl 48 normally holding said pawl in position so that the tooth 52 thereof depends from the other end of the pawl in position to engage the lug 53 upon the adjacent spinning wheel actuating arm 54 as will be later described.

These spinning wheel actuating arms correspond in number to the spinning number wheels 13 and are all rigidly connected at their lower ends to the shaft 55 which is journaled in the side plates 11. One or more coil springs 56 are connected to the spinning wheel actuating arms 53 and to the rear portion of the adjacent side plate 11 for normally holding these arms in the rearward position as indicated in Figs. 1 and 2.

A pawl 57 is pivoted as at 58 upon the upper end of each actuating arm 54, the lower end 59 of each pawl contacting a stop lug 60 on the actuating arm 54 as shown in Fig. 2.

20 A ratchet wheel 61 is fixed upon each spinning number wheel 13 and arranged to be engaged by the pawl 57 on the corresponding actuating arm 54 when these arms are swung upon their pivotal points as will be later described.

25 The ribbon and stamping actuating bar 46 is mounted for horizontal movement upon the adjacent side plate 11 of the frame, said bar having the longitudinal slot 62 therein slidably mounted upon the studs 63 which are attached to the adjacent side plate 11.

30 A coil spring 64 is connected to the depending lug 65 near the forward end of the actuating bar 46 and to the adjacent side plate 11 at a point toward the rear end of the actuating bar as indicated at 66 for the purpose of normally urging the actuating bar 46 to the rearward or initial position as shown in the drawings.

35 At the forward end of the actuating bar 46 a pawl 67 is pivoted as at 68 and rests upon the inturned angular stop lug 69 on the actuating bar so that the depending forward end 70 of the pawl will contact the lug 71 on the stamping arm 72, which is pivoted intermediate its ends as at 73 on the adjacent side plate 11, a coil spring 74 being connected at its upper end to the lower end of the stamping arm as indicated at 75 and at its lower end to the base plate 10 as indicated at 76 in order to normally urge the stamping arm toward upright position.

40 The upper end of the stamping arm has a rubber pad 77 thereon located adjacent to the front sides of the printing wheels 16, the paper tape 19 passing down from the paper guide plate 22 between the printing wheels and said rubber pad.

45 A typewriter ribbon 78 is located between the paper tape and the printing wheels and the ends of said ribbon are wound upon typewriter ribbon spools 79 of any usual and ordinary construction having the usual mechanism (not shown) for unwinding the ribbon from one spool and winding it onto the other spool as is customary in adding machines, cash registers, typewriters and similar machines.

50 A housing indicated generally at 80 covers the mechanism above described and has at its upper rear portion the window 81 through which one numeral on each spinning number wheel is always visible. This housing also has an opening 82 in its upper forward portion, directly above the paper guide plate 22, the rear portion of said opening being covered by a transparent panel of any suitable material as indicated at 23.

55 In the operation of the machine the operator writes with a pencil, pen or the like through the front, or uncovered portion, of the opening 82

upon the portion of the paper tape resting upon the paper guide plate 22, writing the number which he guesses will be displayed by the number wheels upon the next operation of the machine.

He then grasps the knob 34 upon the top of the operating lever and pulls it forward starting the mechanism in operation. As the operating lever is thus pulled forward the main actuating arm 35 moves forward carrying with it the pawl 36 which is engaged with the ratchet wheel 38 upon the rubber roll 30 rotating the rubber roll and through frictional contact with the used paper roll 24 rotating the same in a direction to wind the paper tape thereon and simultaneously unwind an equal amount of the paper tape from the paper stock roll 20, moving the number which the operator has just written upon the paper tape to a point beneath the transparent panel 83 so that this portion of the paper tape is no longer accessible to the operator and cannot be changed by him; although the written number thereon remains visible through the transparent panel.

The rotation of the rubber roll and the paper spools is stopped when the upper end 39 of the pawl 36 contacts the pawl stop 41 lifting the pawl out of contact with the ratchet wheel 38 stopping the movement of the rubber roll and the paper tape.

While the above operation is taking place the finger 45 on the upper end of the main actuating arm 35 has continued to move forward moving with it the ribbon and stamping actuating arm 46, and the depending tooth 52 of the pawl 48 upon the main actuating arm has continued to move the lug 53 on the spinning wheel actuating arm and is moving the pawl forward.

As this motion continues the upper end of the stamping arm 72 is being moved forwardly upon its pivot by contact of the forward end 70 of the pawl 67 upon the ribbon and stamping actuating bar 46 with the lug 71 on the stamping arm 72.

This movement continues until the pawl 48 on the main actuating bar slips off of the lug 53 on the spinning wheel actuating arm permitting the spring 56 to snap these spinning wheel actuating arms back to the position shown in Figs. 1 and 2, the pawls 57 thereon engaging the ratchets 61 on the spinning number wheels 13 spinning said wheels independently.

As the wheels come to a stop by means of the balls 84 located within the hollow wheels and each ball comes to rest at the bottom of its wheel within one of the recesses 85 which correspond in position to the numerals on the outside of the wheels, only one numeral upon each wheel will be displayed through the windows 81 in the housing 80.

The printing wheels 16, being geared to the respective number wheels by means of sprocket and chain connections illustrated and above described, will have come to rest in such position that the raised numerals or type thereon positioned toward the paper tape will correspond to the numbers on the number wheels displayed through the windows 81.

As the pawl 67 upon the actuating bar 46 slips from engagement with the lug 71 on the stamping arm, the spring 74 will snap the stamping arm backward striking the paper tape and typewriter ribbon against the printing wheels on the paper type printing on the paper tape the number which is displayed on the number wheels through the window 81.

The ribbon and stamping actuating bar 46 may

operate the usual mechanism (not shown) for unwinding the typewriter ribbon from one ribbon spool and winding it onto the other spool with each operation of the machine, as is customary in the operation of adding machines, typewriters and similar mechanism.

It will be seen that the number wheels are assured of coming to rest "on" a number and not elsewhere by means of the ball inside of each wheel tending to come to rest at the lowest possible point and stopping the wheel in such position that one of the recesses 85 therein is always at the bottom of the wheel and a numeral on each wheel is in position to be displayed through the windows 81.

It will thus be obvious that by means of a simple mechanism, put into motion by the pulling of the operating lever, the number which the operator has guessed and written upon the tape is immediately moved away from the opening 82 to a point where it is still visible but inaccessible beneath the transparent panel 83; the number wheels are rotated and stopped in such position that a number made up of one numeral or digit on each wheel is displayed through the windows 81 and this number is printed upon the paper tape so that a printed record of each operator's guess and of the number which is obtained by that operation of the machine remains within the machine upon the paper tape.

I claim:

1. A spinning game comprising a housing, a plurality of independently rotatable number wheels in the housing, a window in the housing through which one number on each wheel is displayed, means for rotating the wheels, means for bringing each wheel to a stop with one of the numbers thereon displayed through said window, there being an opening in the housing, means for positioning a paper tape within the housing adjacent to said opening, whereby a number may be written upon the paper tape prior to the rotation of the wheels, a second window in the housing adjacent to said opening and having a transparent cover through which the paper tape is visible but normally inaccessible, and means controlled by said means for rotating the wheels for moving the paper tape within the housing toward said last named window to move the written number thereon away from said opening and to a position where it is visible through the transparent cover of said last named window before the wheels are brought to a stop, whereby said written number will be normally inaccessible but visible for comparison with the numbers on the wheels displayed through the first named window.

2. A spinning game comprising a housing, a plurality of independently rotatable number wheels in the housing, a window in the housing through which one number on each wheel is displayed, printing means operatively connected to each wheel, means for positioning a paper tape within the housing adjacent to said printing means, means for rotating the wheels, means for bringing each wheel to a stop with one of the numbers thereon displayed through said window, means operating the printing means for printing said numbers on the paper tape as the wheels are brought to a stop, there being an opening in the housing through which a number may be written upon the paper tape prior to the rotation of the wheels, a second window in the housing adjacent to said opening and having a transparent cover through which the paper tape is visible but normally inaccessible, and means controlled by said

means for rotating the wheels for moving the paper tape within the housing toward said last named window to move the written number thereon away from said opening and to a position where it is visible through the transparent cover of said last named window before the wheels are brought to a stop, whereby said written number will be normally inaccessible but visible for comparison with the numbers on the wheels displayed through the first named window.

3. A spinning game comprising a housing, a plurality of independently rotatable number wheels in the housing, a window in the housing through which one number on each wheel is displayed, a printing wheel operatively connected to each number wheel, means for positioning a paper tape within the housing adjacent to said printing wheels, means for rotating the number wheels, means for bringing each number wheel to a stop with one of the numbers thereon displayed through said window, means operated by the number wheel rotating means for printing said number on the paper tape by the corresponding printing wheel, there being an opening in the housing through which a number may be written upon the paper tape prior to the rotation of the number wheels, a second window adjacent to said opening and having a transparent cover through which the paper tape is visible but normally inaccessible, and means controlled by said means for rotating the wheels for moving the paper tape within the housing toward said last named window to move the written number thereon away from said opening and to a position where it is visible through the transparent cover of said second window prior to the printing operation, whereby said written number will be normally inaccessible but visible for comparison with the numbers on the wheels displayed through the first named window.

4. A spinning game comprising a housing, a plurality of independently rotatable number wheels in the housing, a window in the housing

through which one number on each wheel is displayed, a printing wheel operatively connected to each number wheel, means for positioning a paper tape within the housing adjacent to said printing wheels, means for rotating the number wheels, means for independently bringing each number wheel to a stop with one of the numbers displayed through said window, means operated by the number wheel rotating means for printing said number on the paper tape by the corresponding printing wheels, there being an opening in the housing through which a number may be written on the paper tape prior to the rotation of the number wheels, a second window adjacent to said opening and having a transparent cover through which the paper tape is visible but normally inaccessible, and means controlled by said means for rotating the wheels for moving the paper tape within the housing toward said last named window to move the written number thereon away from said opening and to a position where it is visible through the transparent cover of the last named window prior to the printing operation whereby said written number will be normally inaccessible but visible for comparison with numbers on the number wheels displayed through the first named window.
